TELEPHONE DIAL LOCK

Sam Reisner, Santa Monica, Calif., assignor to Osco Corporation, a corporation of California

Filed Aug. 17, 1966, Ser. No. 3,498

Term of patent 14 years

(Cl. D50—7)

FIG. 1

FIG. 2

FIG. 5

FIG. 3

FIG. 6

FIG. 4

FIGURE 1 is a perspective view of a telephone dial lock, showing my new design, the dial member and telephone is shown in broken lines for purposes of illustration only;

FIGURE 2 is a side elevational view thereof;

FIGURE 3 is a top plan view thereof;

FIGURE 4 is a bottom plan view thereof;

FIGURE 5 is a front view thereof; and,

FIGURE 6 is a rear view thereof.

The dominant features of my design are shown in solid lines.

I claim:

The ornamental design for a telephone dial lock, substantially as shown and described.
